UNITED STATES PATENT OFFICE.

ZACHARY TAYLOR UBIL AND EDWARD UBIL, OF MORTON, PENNSYLVANIA.

SIGN-DISPLAYING DEVICE.

No. 887,879.

Specification of Letters Patent.

Patented May 19, 1908.

Application filed November 14, 1906. Serial No. 343,350.

To all whom it may concern:

Be it known that we, ZACHARY TAYLOR UBIL and EDWARD UBIL, citizens of the United States, residents of Morton, Delaware county, State of Pennsylvania, have invented a new and useful Sign-Displaying Device, of which the following is a specification.

Our invention relates to improvements in sign displaying devices.

Our object is to provide improved mechanism for displaying one after the other of a series of sheets or cards containing printed or illustrated subject matter. This mechanism is also adapted to display first one side and then the other side of each of said sheets or cards.

Our device is especially adapted for operation in connection with passenger carrying vehicles. The actuating force being a pendulum adapted to be swung by the oscillations of the vehicle.

Referring to the drawings:—Figure 1 is a plan view of our device with the cards omitted. Fig. 2 is a front elevation of the same with the cards omitted. Fig. 3 is a section on line 3, 3 of Fig. 1 with the cards included. Fig. 4 is a detail of a display card in perspective with the supporting pins engaged in the notches. Fig. 5 is a fragmentary view of the card with the supporting pin disengaged from the notch. Fig. 6 is an elevation of the pawl and ratchet operated by the pendulum.

Similar numerals refer to similar parts throughout the several views.

Our invention comprises the two wheels 9 and 10 provided with a series of apertures around its circumference in which are loosely seated the slotted pins 11 as clearly shown in Figs. 1 and 2. The wheels 9 and 10 are loosely mounted on the stationary shaft 31 supported by the standards 12.

Wheel 9 is provided with gear teeth on its outer periphery adapted to mesh with the pinion 14. The slotted pins 11 are adapted to receive the cards 15 as indicated in Figs. 3, 4 and 5, that is, each card is secured on opposite sides in the slots of a pair of said pins 11, one of each pair being in wheel 9 and the other in wheel 10. Circular guards 16 and 17 are secured to the stationary standards 12, close to the outer sides of wheels 9 and 10 as shown in Figs. 1 and 2. These guards have part of their extension closer to the wheel 55 and part more removed therefrom, and are adapted to engage the heads of pins 11 to

move them inwardly through the wheels at one period of the wheels rotative movement, and to permit their actuation in the opposite direction at other periods of said movement. 60 The cards 15 are provided with the notches 18 having inclined sides. These notches are located in the middle of the opposite ends of each card and are adapted to coöperate with the pins 11 for the purpose hereinafter to be 65 described.

On the shaft 19 which is suitably supported by brackets such as 20, is hung the pendulum 21 carrying the arm 22 with the pawl 23. Keyed to shaft 19 is the ratchet 24 for co-operating with the pawl 23. The beveled gear wheel 25 which is also keyed to shaft 19 coöperates with beveled gear wheel 26, keyed to shaft 27 to which is also keyed the pinion 14. It will thus be seen that by a rocking or oscillating or jarring motion of the vehicle, in the required directions the pendulum 21 will be oscillated to cause the ratchet and pawl actuation of the rotative parts. A second pendulum 28 is similarly 75 mounted on shaft 27 and operates the pawl 29 and ratchet 30 on said shaft 27 to actuate pinion 14.

It will be understood that the oscillation of the vehicle in directions in a plane at right angles with that required to move pendulum 21 will serve to move the pendulum 28 to cause the actuation of the pinion 14. In other words, the arrangement of the pendulums to sweep in planes at right angles with each other, will serve to utilize, to the fullest extent, the various jarring or oscillating movements of the vehicle.

As above indicated the rotation of pinion 14 which is meshed with the gear teeth on 95 wheel 9 will serve to cause the rotation of wheel 9.

Wheel 9 is supported loosely on a fixed shaft 31 which is secured from rotation by the set-screws 32 in standards 12. The purpose of having shaft 31 rigid against rotation is to furnish a support for the brackets 33, the purpose of which will be hereinafter described. In brackets 33 is journaled a countershaft 34 upon which are keyed pinions 35 and 36 meshing with pinions 37 which is connected with wheel 9 and pinion 38 which is connected with wheel 10, by which means an equal movement in the same direction will be communicated from the wheel 9 to wheel 10. 100 105 110

The operation of our device is as follows:— It will be understood that the pawl and

ratchet actuation will be such as to move wheels 9 and 10 in the direction of the arrow as shown in Fig. 3, and it will also be understood that this rotative movement of wheels 5 9 and 10 will be a step by step movement. In Fig. 3 the cards are shown in the various positions which they will assume as the wheels are slowly rotated. Three of the cards to the left and below the center of the wheels, 10 are supported by the block or projection 39. As the third card counting from the left below the center of the wheel, looking at Fig. 3, is moved in a position from which it clears block 39, its pins 11, will have traveled down 15 the sides of the cards to near enough the middle to encounter the inclined edges of notches 18. At the same time the portion of guards 16 and 17 will have been encountered by the pins 11 to cause the pins to move forward to 20 toward the card and securely engage the card in said notches 18. In this position the card is held first in a perpendicular position, by gravity and then in a gradually inclining position as the wheel continues to rotate, until, towards 25 the upper part of the wheel, it will first become approximately horizontal and then inclined so that the right hand side will be higher than the left hand side. This inclination will increase until the card becomes 30 substantially vertical again, but inverted from the position at which it started from the lower left hand side of the wheel. In the position shown in the extreme left hand side of Fig. 3 above the wheel centers, the opposite side of the card will be displayed through 35 the aperture 40 and again through the aperture 41, from the side which was displayed prior to its last rotation around the wheel. It would also be understood that after the 40 cards come into the upper left hand quadrant of the wheel the guards 16 and 17 will be withdrawn again from the side of the wheel to permit the pins 11 to be forced out of the notches by the inclined sides thereof, thus 45 permitting the cards to drop down upon the projection 42 of bracket 33. This construction of the guards 16 and 17 is clearly shown in Fig. 1. The card furthest to the left above the center of the wheel will rest upon this 50 projection 42 and be displayed through aperture 40 until the wheels 9 and 10 rotate sufficiently to push the card beyond the edge of 42. This position, which is only a momentary one, is shown in Fig. 3, as that of the 55 card now furthest to the left above the center of the wheel. From this position it will fall immediately to substantially the position shown by the card furthest to the left in Fig. 3, below the center of the wheel. In this last 60 position the card rests upon projection 39 and is displayed through aperture 41, until another card falls in front of it. Each card is gradually dragged off projection 39 by the

rotation of wheels 9 and 10 and the operation continues as above described. By the mechanism above described a large number of sign cards can be arranged in a very small space and displayed one after the other, first one side and then the other side. By this device also the only motive power required for its 70 operation is furnished by the oscillating rocking, and sudden starting and stopping movements of the vehicle

What we claim is:—

1. In a sign displaying device, the combination of a rotative element provided with a plurality of pairs of oppositely disposed slotted pins loosely seated therein, a plurality of cards carried by the said pairs of slotted pins, and having a limited movement in said slots, 80 stops for limiting said movement, and pendulum actuated mechanism for operating the rotative element.

2. The combination of a rotative element, a plurality of oppositely disposed pairs of 85 slotted pins carried thereby, a plurality of display elements having recesses with inclined margins at their opposite ends for co-operating with the slotted pins, one of each pair of slotted pins being longitudinally 90 movable, and a guard for co-operating with said longitudinally movable pins positioned at one side of the path of travel of the rotative element, one part of said guard being closer to the rotative element than another 95 part, and adapted to limit the longitudinal movement of the slotted pins, substantially as and for the purpose described.

3. In a sign displaying device, a plurality of display cards notched at their opposite 100 ends, a step by step rotative structure, slotted pins loosely seated therein adapted to co-operate with the notches to support the cards and stationary guards for controlling the movement of the pins as the structure rotates, permitting their disengagement with the notches during part of the rotation and preventing such disengagement during another part of the rotation, substantially as and for the purpose described.

4. In a sign displaying device, a plurality of display cards, a step by step rotative structure, slotted pins loosely seated therein in oppositely disposed pairs for supporting the cards, and stationary guards for controlling the longitudinal movement of the pins as the structure rotates, to prevent the independent movement of the card with respect to its supporting pins during part of said rotation and to permit such independent movement during another part of such rotation.
